CHAIR FOR USE IN CANOES AND THE LIKE

Filed March 8, 1928

By *Watson E. Coleman*
Attorney

UNITED STATES PATENT OFFICE.

EDWIN C. LEE, OF AUGUSTA, MAINE.

CHAIR FOR USE IN CANOES AND THE LIKE.

Application filed March 8, 1928. Serial No. 260,050.

This invention relates to chairs for use in canoes or other small boats and has for an important object thereof the provision of a device of this character which might likewise 5 be conveniently employed as a beach chair or as a fireside chair or in the camp.

An important object of the invention is to provide a structure which will provide a comfortable seat and back therefor which will 10 be substantially unaffected by changing weather conditions.

A still further object of the invention is to provide a device of this character which may be relatively cheaply manufactured and 15 which, at the same time, will be durable and efficient in service.

A further object of the invention is to provide a device of this character which is foldable, so that it may be stored in a comparative- 20 ly small space.

These and other objects I attain by the construction shown in the accompanying drawings, wherein for the purpose of illustration is shown a preferred embodiment of my in- 25 vention and wherein:—

Figure 1 is a perspective view of a chair constructed in accordance with my invention;

Figure 2 is a side elevation thereof, the back of the chair being illustrated in solid lines in 30 its normal position and in dotted lines in the position which it assumes for storage.

Referring now more particularly to the drawings, the numeral 10 generally designates 35 a base comprising side members 11 connected by rungs or dowels 12. Adjacent their rear ends, these side members are connected by a transversely extending rustproof metal bar 13, the purpose of which will presently appear.

The side members 11 are preferably relatively shallow. Secured to the upper surface 40 of the side members is a U-shaped bow 14, the open end of which is directed toward the rear end of the base. The arms of the bow adja- 45 cent the open end thereof are connected by a transverse bar 15 and upon this bar and the bow is mounted a woven rawhide or gut seat 16, the weave of which preferably corresponds to that employed in the construction of snow- 50 shoes.

A back bow 17 is provided, the arms 18 of which, adjacent their lower ends, are pivoted 55 at 19 to blocks 20 secured to the upper surface of the arms of the bow 14 adjacent the rear ends thereof. Above the pivots, the arms 18 are connected by a cross bar 20^a and this cross bar and the bow provide supports for a woven back 21 constructed of the same material and in the same fashion as the seat 16. The ends 60 of the arms 19 project beyond the pivots and when the back is in raised position and inclines slightly to the rear from the vertical, the lower ends of these arms engage against the rear rung 12 and rod 13 to limit movement of the back. From this position, the bow 17 65 may be swung to a position where it is superimposed upon the bow 14 and the device is collapsed for transportation.

It will be obvious that a device of this character may be relatively cheaply produced and 70 will be very durable and efficient in service since the woven back and seat are of such character that they will not be affected by moisture or changes in temperature.

Since the construction hereinbefore set 75 forth is capable of a certain range of change and modification without materially departing from the spirit of the invention, I do not limit myself to such specific structure except as hereinafter claimed.

I claim:—

In a device of the type described, a base including side members, a U-shaped bow secured to the upper surfaces of the side members and having its open end rearwardly directed, a 85 second U-shaped bow operatively pivotally connected with the first named bow at the rear end thereof and swingable about the pivots thereof from a position where it is substantially vertically disposed to a position where it 90 overlies and is superimposed upon the first named bow, transverse bars extending across the open mouths of the bows and a woven net connecting said bows and their associated bars.

In testimony whereof I hereunto affix my signature.

EDWIN C. LEE.
